(57) **CLAIM**

The ornamental design for a bed step stool, as shown and described.

DESCRIPTION

FIG. 1 is a rear and left side perspective view of a bed step stool.

FIG. 2 is a front elevational view of the bed step stool.

FIG. 3 is a rear elevational view of the bed step stool.

FIG. 4 is a left side elevational view of the bed step stool.

FIG. 5 is a right side elevational view of the bed step stool.

FIG. 6 is a top plan view of the bed step stool; and,

FIG. 7 is a bottom plan view of the bed step stool.

The broken lines shown in FIGS. 1-7 are included for the purpose of illustrating environmental elements only and form no part of the claimed design.

1 Claim, 5 Drawing Sheets
